Hoover Innovation cleaner Model U5045, Dec. 1987.

Primary Examiner—Ruth McInroy

CLAIM

The ornamental design for a suction cleaner upper portion, as shown and described.

DESCRIPTION

FIG. 1 is a left side elevational view of a suction cleaner upper portion showing my new design;

FIG. 2 is an enlarged front elevational view thereof; FIG. 3 is an enlarged right side elevational view thereof;

FIG. 4 is an enlarged rear elevational view thereof;

FIG. 5 is an enlarged top plan view thereof; and,

FIG. 6 is an enlarged bottom plan view thereof.

The portion of the vacuum cleaner shown in broken lines in FIG. 1 is shown for illustrative purposes only and forms no part of the claimed design.
